UNITED STATES PATENT OFFICE.

JOHN H. ASHBAUGH, OF WILKINSBURG, PENNSYLVANIA, ASSIGNOR TO WESTINGHOUSE ELECTRIC & MANUFACTURING COMPANY, A CORPORATION OF PENNSYLVANIA.

REGULATOR SYSTEM.

Application filed March 14, 1921. Serial No. 452,161.

To all whom it may concern:

Be it known that I, JOHN H. ASHBAUGH, a citizen of the United States, and a resident of Wilkinsburg, in the county of Allegheny and State of Pennsylvania, have invented a new and useful Improvement in Regulator Systems, of which the following is a specification.

My invention relates to electric regulators and has special relation to the vibratory type of regulator.

It is the object of the present invention to extend the working range of the regulator over wider limits than heretofore attained and to accomplish this result with greatly simplified apparatus.

It has heretofore been proposed to extend the operating range of the control relays of a so-called "Tirrill" regulator by including in series relation with the relays a resistor which is cut into the circuit by the action of an auxiliary electromagnet whenever the exciter voltage falls below a predetermined point. Such a regulator is shown in the application of A. A. Tirrill, Serial No. 267,647, filed Dec. 20, 1918. Such an arrangement will permit an operating range of one to four for the regulator or, for example, the regulator will respond over a range of 35 to 150 volts when used in conjunction with a 125-volt exciter.

The present invention also contemplates connecting a resistor or other current-consuming or impedance device in series relation with the operating relays. However, this resistor is controlled by means of an electromagnet connected in parallel relation with the operating relays. Thus, this electromagnet will vibrate at the same rate as the operating relays and will control the energization thereof in accordance with the variations in supply-circuit voltage.

Likewise, the electromagnet controls its own energization by reason of the parallel connection with the operating relays of the regulator. It will thus be apparent that the range of operation of the regulator is extended over wider limits by reason of the varying energization of the controlling electromagnet for the resistor in circuit with the operating relays of the regulator.

Referring to the drawing, the single figure is a diagrammatic illustration of circuits and apparatus embodying my invention.

The system to which the present invention

is illustrated as applied, comprises a main generator 1 having an armature 2 and a field-magnet winding 3 connected to a suitable polyphase supply circuit comprising conductors 4, 5 and 6. The field-magnet winding 3 has connected thereto an exciter generator 7 having an armature 8 and a field-magnet winding 9. Connected in circuit with the field-magnet winding 9 is an adjustable rheostat 11. The rheostat 11 is controlled through the operation of a regulator 12 which includes a main control magnet 13, a vibratory control magnet 14 and relays 15 and 16. The main control magnet 13 is connected across supply conductors 4 and 5 by means of a transformer 17.

The core armature 18 of the electromagnet 13 is connected to a floating lever 19 which, in turn, is connected to a bell-crank lever 21, pivoted at 22. The core or armature 23 of the vibrating magnet 14 is connected to the bell-crank lever by means of a spring 24. A counterweight 25 is connected to the outer end of the bell-crank lever 21 to assist the pull of the main control magnet. Connected to the floating lever 19 is the vibratory contact member 26.

Contact member 26 co-operates with a stationary contact member 27 which is connected to one terminal of the armature 8 of the exciter machine 7. The circuit which includes the vibratory contact member 26 extends through the coils 28 and 29 of relays 15 and 16, respectively, and through a resistor 31, to the opposite terminal of the exciter armature 8.

Operating relay 15, when energized, controls a shunt circuit through contact members 32 and 33 around the adjustable rheostat 11 in circuit with the exciter field winding 9. Operating relay 16, when energized, controls a shunt circuit through contact members 34 and 35 around a resistor 36 in circuit with the coil of the vibratory control magnet 14.

Thus, any variations in the electrical condition of the supply conductors will vary the energization of the main control magnets 13 and 14 to produce a vibratory action of the main contact members 26 and 27. This action will intermittently energize the coils 28 and 29 of the operating relays 15 and 16 in accordance with the excitation of the main generator field-magnet winding 3. The latter action, in turn, will vary the en-

ergization of the exciter field-magnet winding to vary the excitation of the main generator field-magnet winding 3.

The foregoing apparatus and operation are similar in all respects to the structure and operation of the well-known "Tirrill" regulators.

It will be apparent that the energization of the coils 28 and 29 of the operating relays 10 15 and 16 may be varied if the resistor 31, which is in circuit therewith, is varied. In the present invention, this variation is accomplished by the electromagnet 37 which is an inverted electromagnet and, hence, 15 operates in inversely proportional relation to the variations in the exciter voltage.

Electromagnet 37 comprises an energizing coil 38 connected in parallel circuit relation with the coils 28 and 29 of relays 15 and 16, 20 and an armature 39 carrying contact member 41 which co-operates with contact member 42 to complete a shunt circuit for the resistor 31. By reason of the connection of the winding 38 in parallel relation with the 25 windings 28 and 29, the electromagnet 37 pulsates in unison with the operating relays 15 and 16. The voltage at which the electromagnet 37 will respond may be adjusted by adjusting the tension of spring 43, secured 30 to the armature 39, in the customary manner. From the preceding description, it will be apparent that, under normal voltages, the vibratory relay 15 will control the effective 35 value of the rheostat 11 in circuit with the exciter field winding 9 in accordance with variations in the supply-circuit voltage. By reason of the vibratory action of the armature 39 of the electromagnet 37, the effective 40 value of the resistor 31 in this circuit will be controlled proportional to variations in the exciter voltage. By reason of the character 45 of the electromagnet 37, these variations will occur at an inverse ratio to the variations in the operation of the relay 15.

It will be noted that the resistor 31 is in circuit with the energizing coil 38 of the electromagnet 37 as well as in the circuit of the windings 28 and 29 of relays 15 and 16. Accordingly, the electromagnet 37, in 50 addition to varying the energization of the windings of the operating relays, also varies the energization of its own winding. Hence, the range of operation of the regulator is extended practically indefinitely by 55 reason of the varying energization of the energizing winding of the electromagnet controlling the extension of the operating range.

Modifications in the system and arrangement and location of parts may be made within the spirit and scope of my invention, and such modifications are intended to be covered by the appended claims.

I claim as my invention:—

1. In a regulator of the field excitation

of a dynamo-electric machine, the combination with a device for controlling the variations of said field excitation having a winding energized in accordance with such variations, of a vibratory device also actuated in 70 accordance with the variations of the field excitation and controlling the degree of energization of said winding.

2. In a regulator for maintaining a constant voltage upon a supply circuit, the combination comprising contact members, a lever system connected to said contact members, control magnets therefor, a plurality of relays controlled by said contact members, a resistor in circuit with said relays, and vibratory means for controlling said resistor. 75

3. In a regulator for maintaining a constant voltage upon a supply circuit, the combination comprising contact members, control magnets therefor, a plurality of relays controlled thereby, a resistor in circuit with 80 said relays and vibratory means for controlling said resistor. 85

4. In a regulator, the combination comprising switch mechanism, control magnets therefor, relays controlled by said mechanism and vibratory means for varying the operating range of said relays. 90

5. In a system for maintaining a constant voltage upon a supply circuit, the combination with a dynamo-electric machine connected to said circuit, and an exciter therefor, of a regulator comprising a relay energized in accordance with the exciter 100 voltage and vibratory means for extending the range of operation of said relay actuated in accordance with the exciter voltage. 105

6. In a regulator, the combination comprising contact members, a lever system connected to said contact members, control magnets therefor, relays governed by said contact members having a resistor in circuit therewith, and a vibratory electromagnet for controlling a shunt circuit for said resistor. 110

7. In a regulator for governing the field excitation of a dynamo-electric machine, the combination comprising electroresponsive means governed in accordance with said field excitation having a resistor in circuit therewith and a vibratory electromagnet adapted to control a shunt circuit for said resistor. 115

8. In a regulator for maintaining a constant voltage upon a supply circuit, the combination comprising contact members, a lever system connected to said contact members, control magnets therefor, a plurality of relays controlled by said contact members, a resistor in circuit with said relays, and an electromagnet connected in parallel relation 120 with said relays and adapted to control the effective value of said resistor. 125

9. In a regulator, the combination comprising vibratory contact members, control means therefor, and a plurality of electro- 130

responsive devices controlled by said contact members having a resistor in circuit therewith, one of said devices being adapted to control the effective value of said resistor in said circuit.

10. In a regulator, the combination comprising contact members, control means therefor, and a plurality of parallel-connected electroresponsive devices controlled by said contact members and having a resistor in circuit therewith, one of said devices being adapted to control a shunt circuit for said resistor.

11. The combination with a dynamo-electric machine, an exciter therefor having an armature and a field-magnet winding and a rheostat in circuit with said winding, of a regulator comprising a vibratory relay energized in accordance with the exciter voltage and adapted to control a shunt circuit for said rheostat, the periodicity of said relay being proportional to the voltage of said machine, a resistor in circuit with said relay, and an electromagnet adapted to vary the effective value of said resistor in said circuit in inverse proportion to the periodicity of the first-mentioned relay.

12. The combination with a regulator, of means for extending the range of operation thereof comprising a resistor in circuit with said regulator and vibratory electroresponsive means for controlling said resistor.

13. In a regulator for maintaining a substantially constant voltage upon a supply circuit, the combination comprising electroresponsive means energized from a variable voltage source having an impedance device in circuit therewith and vibratory electroresponsive means also energized from said source for automatically varying the effective value of said impedance device.

14. In a regulator, the combination comprising electroresponsive means energized from a variable voltage source having a current-consuming device in circuit therewith and vibratory electroresponsive means for automatically controlling said device to determine the range of operation of said regulator.

15. In a regulator, the combination comprising electroresponsive means energized from a variable voltage source having a variable resistor in circuit therewith and automatic means for controlling the mean effective value of said resistor to determine the range of operation of said regulator.

16. In a regulator, the combination comprising electroresponsive means energized from a variable voltage source having a variable resistor in circuit therewith and vibratory means for controlling said resistor to determine the range of operation of said regulator.

17. In a regulator, the combination comprising contact members, electroresponsive

means controlled thereby and vibratory means co-operating therewith for varying the energization of said first-mentioned means to determine the range of operation of said regulator.

18. In a regulator, the combination comprising switch mechanism, electroresponsive means controlled thereby, and associated vibratory means for determining the operating range of said electroresponsive means.

19. The combination with a supply circuit, of a dynamo-electric machine connected thereto having an exciter generator co-operating therewith, a regulator for maintaining a constant voltage upon said supply circuit having an impedance device in circuit therewith, and vibratory means actuated in accordance with the exciter voltage for controlling said device.

20. In a regulator for governing the field excitation of a dynamo-electric machine having a current-consuming device in circuit with said regulator, vibratory means adapted to control said device in accordance with said field-excitation.

21. The combination with a regulator, of means for extending the range of operation thereof comprising a current-consuming device associated with said regulator, and vibratory means for controlling said device.

22. In a regulator for maintaining a substantially constant voltage upon a supply circuit connected to a variable voltage source, the combination comprising an electromagnet energized from said source having a resistor in circuit therewith, and vibratory means connected in parallel-circuit relation to said electromagnet for automatically varying the effective value of said resistor.

23. In a regulator for maintaining a substantially constant voltage upon a supply circuit connected to a variable voltage source, the combination comprising electroresponsive means energized from said source having a resistor in circuit therewith, and co-operating vibratory electroresponsive means connected in parallel-circuit relation to said first-mentioned electroresponsive means for automatically regulating the effective value of said resistor.

24. The combination with a regulator, of means for extending the range of operation thereof comprising a resistor in circuit with said regulator, and vibratory electroresponsive means connected in parallel-circuit relation to said regulator for controlling said resistor.

25. In a regulator for maintaining a substantially constant voltage upon a supply circuit, the combination comprising electroresponsive means energized from a variable voltage source having an impedance device

in circuit therewith, and vibratory electro-responsive means connected in parallel-circuit relation to said first-mentioned electro-responsive means for automatically varying 5 the effective value of said impedance device.

26. In a regulator, the combination comprising electroresponsive means energized from a variable voltage source having a current-consuming device in circuit therewith, 10 and vibratory electroresponsive means connected in parallel-circuit relation to said first-mentioned means for automatically controlling said device to determine the range of operation of said regulator.

27. In a regulator, the combination comprising contact members, electroresponsive means controlled thereby, and vibratory means connected in parallel-circuit relation

to said first-mentioned means for varying the energization thereof to determine the 20 range of operation of said regulator.

28. In a regulator for maintaining a substantially constant voltage upon a supply circuit, the combination comprising electroresponsive means energized from a variable 25 voltage source having an impedance device in circuit therewith, and electroresponsive means also energized from said source for automatically varying the effective value of said impedance device at a ratio inversely 30 proportional to the variations of said variable voltage source.

In testimony whereof, I have hereunto subscribed my name this 26th day of February 1921.

JOHN H. ASHBAUGH.
